DESIGN FOR A BUTTON

Emily L. Pitkin, New York, N. Y.

Application February 27, 1940, Serial No. 90,549

Term of patent 7 years

To all whom it may concern:

Be it known that I, Emily L. Pitkin, a citizen of the United States, residing in the Borough of Manhattan, city, county, and State of New York, have invented a new, original, and ornamental Design for a Button, of which the following is a specification, reference being had to the accompanying drawing, forming part thereof.

Fig. 1 is a top plan view of a button showing my design;

Fig. 2 is a side view of the button; and

Fig. 3 is a front end view of the button inverted.

I claim:

The ornamental design for a button, as shown.
EMILY L. PITKIN.
